UNITED STATES PATENT OFFICE.

ALBERT H. ACHER, OF LAKE FOREST, ILLINOIS.

ADJUSTABLE MOLD FORM FOR CONCRETE BEAMS.

Application filed August 20, 1923. Serial No. 658,347.

To all whom it may concern:

Be it known that I, ALBERT H. ACHER, a citizen of the United States, and a resident of Lake Forest, in the county of Lake and State of Illinois, have invented an Improved Adjustable Mold Form for Concrete Beams, of which the following is a specification.

This invention relates to mold forms for casting concrete floor beams.

10 The object of the invention is to provide a mold form for the purpose specified, which is simple in construction, which can be manufactured at small cost as compared with any mold forms for the purpose of which I have 15 knowledge, and which is readily adjustable to provide for varying the size of the mold to adapt it for forming beams of different sizes.

To effect the objects of the invention, my 20 improved mold form comprises the various features and details of construction herein-after described and claimed.

In the accompanying drawings in which my invention is fully illustrated,

25 Figure 1 is a transverse sectional view of a mold form embodying my invention and improvements, as erecting for casting the beam or girder of a concrete floor a section of which is shown in association therewith.

30 Figure 2 is a view substantially similar to Fig. 1, illustrating the adjustability of the mold.

Figure 3 is a fragmentary sectional view on the line 3—3 of Fig. 1; and

35 Figures 4 and 5 are isometric of angle plates forming part of my improved mold.

Referring now to the drawings, my improved mold form consists of a bottom board 1, side boards 2, 2' and angle plates 3, 3' and 4, 4'.

40 When the mold is erected for use, the flanges 5 of the angle plates 3, 3', rest upon and are secured to the bottom board 1, and the flanges 6 of the angle plates 4, 4', rest upon and are secured to the deckings 7, on which the concrete floor proper is to be laid, the flanges 5' and 6' of the angle plates 3, 3' and 4, 4', respectively, being secured to the side boards 2, 2'.

50 The angle plates 3, 3' and 4, 4' are preferably secured to the bottom plate 1, the side plates 2, 2' and the decking 7 by means of nails, said angle plates being provided with rows of nail holes to receive the nails.

55 With the described construction, it is obvious that the width of the mold form may

be varied by securing the angle plates 3, 3' and 4, 4' to the bottom plate 1 and decking 7 with the flanges 5, 5' and 6, 6' thereof, respectively, separated a greater or less distance as may be desired. Also, to provide for varying the depth of the mold form, the flanges 5, 5' and 6, 6' of said angle plates are provided with correspondingly spaced longitudinal and transverse rows or series of nail holes, whereby series of holes in the flanges 5, 5' and 6, 6' of said angle plates may be brought into register with each other, thus permitting said flanges to be secured to the side boards of the mold either in spaced relation or in different overlapped positions.

In use, the bottom board 1 is supported in any suitable manner, as by ledgers 8 secured to the struts 9 which support the stringers 10 on which the decking 7 is laid, and to support the sides of the mold form from bulging outwardly under the weight of the concrete when a beam is cast, braces 11 are inserted between the side boards 2 and the struts 9.

I do not, however, desire to limit myself to the particular means for supporting said mold forms, as my invention contemplates any desired or approved means for this purpose.

The bottom board 1 and side boards 2, 2' not only form supports for the angle plates 3, 3' and 4, 4', but they also very greatly reinforce and strengthen the entire mold structure.

To illustrate the adjustability of the mold, I have in Figs. 1 and 2 of the drawings, respectively, shown the angle plates 3, 3' and 4, 4' secured to the bottom board 1 and side boards 2, 2' in different relations to form mold forms of different sizes, the flanges 5, 5' and 6, 6' being overlapped in Fig. 2 and as not overlapped in Fig. 1.

Also, while I have herein shown and described the plates 3, 3' and 4, 4' as angle plates, my invention contemplates equally the use of other forms of plates, if desired.

I claim—

1. A mold form for casting concrete floor beams comprising bottom and side boards, and two sets of angle bars, flanges of all of which are adapted to be secured to the side boards of the mold form and to define the sides thereof, the other flanges of said sets of angle bars, respectively, being adapted to be secured to the bottom board of the mold form and to extend over and be secured to

the decking on which the floor is to be laid.

2. A mold form for casting concrete floor beams as specified in claim 1, in which the flanges of the angle plates adapted to be secured to the side boards of the mold are provided with correspondingly spaced longitudinal and transverse series of nail holes, whereby series of holes in different plates

may be brought into register with each other to permit said flanges to be secured to the side boards of the mold in overlapped position.

In witness that I claim the foregoing as my invention, I affix my signature this 13th day of August, A. D. 1923.

ALBERT H. ACHER.
